UNITED STATES PATENT OFFICE.

CHESTER I. HALL, OF CHICAGO, ILLINOIS, ASSIGNOR TO CHICAGO ELECTRIC METER COMPANY, OF CHICAGO, ILLINOIS, A CORPORATION OF ILLINOIS.

VARIABLE-RATE METER.

1,178,152.

Specification of Letters Patent.

Patented Apr. 4, 1916.

Application filed November 13, 1911. Serial No. 659,882.

To all whom it may concern:

Be it known that I, CHESTER I. HALL, a citizen of the United States, residing at Chicago, in the county of Cook and State 5 of Illinois, have invented certain new and useful Improvements in Variable-Rate Meters, of which the following is a full, clear, concise, and exact description, reference being had to the accompanying drawings, 10 forming a part of this specification.

My invention relates to an improved construction of variable rate meters by which a consumer of electricity may be charged at one rate for a given range of consumption 15 per unit of time, and at another rate when the consumption exceeds the predetermined amount in the same time.

By my invention I provide means associated with the pressure circuit of the meter so that for different rates of consumption 20 the E. M. F. applied to the pressure circuit is automatically varied. In this way I am able to secure different rates of operation of the meter for different ranges of consumption 25 and this secures the same result as though separate account were kept of the different ranges of consumption and different prices charged for each range, since the entire consumption registered by my variable rate meter may be charged for at a 30 uniform rate.

Figure 1 is a diagrammatic illustration of the apparatus and circuit connections employed in carrying out my invention; Fig. 35 2 shows in a diagrammatic view a modified arrangement of the switching mechanism for changing the rate of operation of the meter.

In the drawing illustrating my invention 40 I have shown a meter of standard construction at 1 in which the moving element 2 has coöperating with it a series winding 3 and a pressure winding 4, the particular type of meter shown being that known in the art 45 as an induction meter. The windings 3 and 4 are connected together by wire 5 which in turn is connected with the terminal 6 of the meter. The other terminal of the winding 3 is connected with the terminal 9 of the

meter, while the other terminal of the pressure winding 4 is connected through the main resistance 7 with the terminal 8 of the meter.

In order that my invention may be readily applied to meters already in use, I preferably arrange the attachment in a separate casing 11 provided with terminals 12, 13, 14 and 15. The terminal 12 is connected with the terminal 9 of the meter by wires 16 and 17 between which the load is connected. The 50 terminal 13 is connected by wire 18 with the terminal 6 of the meter and the wire 18 in turn is connected by wire 19 with one of the main feeders 20. The other main feeder 21 is connected by wire 22 with the terminal 15 of the controlling attachment. Within the casing 11 a wire 23 connects the terminal 12 with one terminal of the solenoid 24, the other terminal of which is connected by wire 25 with the terminal 15 of the controlling mechanism. The solenoid 24 is provided with a plunger 26 connected with a switch 27, the pivotal point of which is connected with the terminal 14 of the controlling mechanism. The switch 27 is provided with a 55 back contact 28 connected by wire 29 with the wire 25. There is also located in the casing 11 a pressure transformer 30 having a primary winding 31 and a secondary winding 32 which are connected together at one 60 end and by means of the wire 33, this common connection is connected with the terminal 13. The other terminal of the primary winding 31 is connected by wire 34 with the wire 25. The secondary winding 32 has a 65 plurality of jacks 35 connected with taps taken from different points of the winding and a plug 36 is provided which is adapted 70 to engage any one of the jacks so that a desired pressure may be impressed upon the 75 pressure circuit of the meter when the switch 27 is actuated. The plug 36 is connected by a flexible conductor 37 with a front contact 38 of the switch 27. The switch 27 is normally maintained in position against 80 its back contact by means of a spring 39 which may be given any desired tension by 85 an adjusting screw 40. The solenoid 24 is 90 95

preferably comparatively long and is provided with an air return path so that the pull exerted upon the core 26 and therefore upon the switch 27, may vary uniformly with the current flow through the solenoid, and further that there may be no greater tendency for the core to remain in one position than another. As a result of the connections described, it will be seen that the switch 27 normally connects the pressure circuit of the meter, including the pressure winding 4 and the main resistance 7, across the main feeders 20 and 21, which supply an electromotive force of proper amount to cause the element 2 to rotate at a normal desired rate. When the load in circuit with the wires 16 and 17 is increased to the permissible limit for the installation, the core or plunger 26 is moved from its back contact 28 into engagement with its front contact 38, and thus the pressure circuit above referred to is interrupted and the pressure winding 4 and resistance 7 are connected with the terminals of the secondary winding 32 of the transformer 30. The transformer 30 may be standard in construction and provided with such a number of taps as to give any desired potential upon the terminals of the pressure circuit of the meter for its abnormal working condition and in this way, the rate of rotation of the moving element 2 may be caused to be greater or less if desired than its normal rate, depending upon the particular conditions of operation. It will be understood that the plug 36 is usually given some particular adjustment when the controlling mechanism is attached to the meter by inserting the plug in a proper one of the jacks 35, and that after this adjustment has been made, the plug 36 is left in such position.

As shown in Fig. 2, the switch 27^a may carry contact mechanisms for interrupting the circuit through the primary winding 31^a when the switch is in normal position against its back contact 28^a, said primary circuit being closed when the switch 27^a is moved to its operated position against the action of the spring 39^a by the plunger 26^a of the solenoid. In this modification the wire 34^a extends from the wire 25^a to the contact 42, and the right-hand terminal of the primary winding 31^a of the transformer is connected by the wire 41 with the contact 43. These contacts are disposed so as to be engaged by the insulated contact plate 44 carried by the switch 27^a when the switch is moved by the plunger 26^a into engagement with the contact 38^a. In this way the transformer is entirely removed from the circuit connections when the current flowing in the load circuit is below a predetermined maximum. Thus it will be understood that I may secure the results described by various equivalent circuit arrangements and that

while the primary winding 31 is shown in Fig. 1 as permanently connected to the main line conductors 20 and 21, that it may be disconnected when not in use by means of extra contacts controlled by the switch 27, as indicated in Fig. 2, if desired. 70

What I claim is:

1. In a variable rate meter, the combination of a pressure circuit normally connected to the line, a work circuit, a pressure transformer, a solenoid in the work circuit, and switching mechanism controlled by the solenoid for switching the terminals of the pressure circuit from the line to the secondary winding of the transformer. 75
2. In a variable rate meter, a work circuit, a pressure circuit, a pressure transformer, and mechanism controlled by the current traversing said work circuit for automatically connecting the pressure circuit either directly to the line or with the secondary winding of said transformer. 80
3. In a variable rate meter, a work circuit, a pressure circuit, and means comprising a transformer and switching mechanism controlled by the current traversing the work circuit for varying the E. M. F. applied to the pressure circuit. 90
4. In a variable rate meter, a work circuit, a pressure circuit, a transformer arranged to have its secondary operatively connected with the pressure circuit and so supply E. M. F. to said pressure circuit, and mechanism automatically actuated when the load exceeds a predetermined maximum operable to so connect the transformer secondary with the pressure circuit. 95
5. A variable rate meter comprising a pressure circuit arranged to receive E. M. F. from a line, transformer means arranged and adapted when connected with the pressure circuit to apply to said pressure circuit E. M. F. of different value than the E. M. F. normally applied to said pressure circuit, and means automatically operable to connect the transformer means with the pressure circuit when the load current varies beyond a certain predetermined limit. 100
6. In a variable rate meter, a work circuit, a pressure circuit, a pressure transformer, mechanism for connecting the pressure circuit either directly to the line or with the secondary winding of said transformer, and means automatically operable to actuate said connecting mechanism when the load current varies beyond a certain predetermined limit. 110
7. In a variable rate meter, a work circuit, a pressure circuit, a pressure transformer, and mechanism for automatically connecting the pressure circuit either directly with the line or with the transformer secondary. 120
8. A variable rate metering mechanism comprising in combination a pressure cir- 130

cuit, a load circuit, and means the operation of which is automatically controlled by the load current adapted to supply an induced E. M. F. to said pressure circuit to vary the 5 rate of operation of the meter when the consumption of energy varies beyond predetermined limits.

In witness whereof, I hereunto subscribe my name this 12th day of November, A. D. 1911.

CHESTER I. HALL.
